CLAIM

The ornamental design for a chemical dispensing brush
for use in flea exterminating, as shown and described.

DESCRIPTION

FIG. 1 is a perspective view of a chemical dispensing brush
for use in flea exterminating showing our new
design.

FIG. 2 is a top plan view thereof.

FIG. 3 is a left end elevation view thereof.

FIG. 4 is a side elevational view, the opposite side being
a mirror image thereof.

FIG. 5 is a right end elevation view thereof.

FIG. 6 is a bottom plan view thereof.

FIG. 1

FIG. 2

FIG. 3

FIG. 4

FIG. 5

FIG. 6
